CLAIM

We claim, the ornamental design for a syringe barrel, as shown and described.

DESCRIPTION

FIG. 1 is an enlarged front perspective view of a syringe barrel showing the claimed design;

FIG. 2 is a front view thereof, the rear view being a mirror image thereof;

FIG. 3 is a top plan thereof;

FIG. 4 is a bottom plan view thereof;

FIG. 5 is a right side view thereof;

FIG. 6 is a left side view thereof;

FIG. 7 is an enlarged view of the outlined box shown in FIG. 1;

FIG. 8 is an enlarged view of the outlined box shown in FIG. 2; and,

FIG. 9 is an enlarged cross-sectional view taken along line 9-9 of FIG. 2.

The broken lines in the drawings illustrate portions of the syringe barrel and form no part of the claimed design.

1 Claim, 5 Drawing Sheets
